(Continued)

Primary Examiner — Michael A. Pratt(74) *Attorney, Agent, or Firm* — Dinsmore & Shohl LLP(57) **CLAIM**

The ornamental design for a firearm as shown and described.

DESCRIPTION

FIG. 1 is an upper perspective view of a design of a firearm; FIG. 2 is a lower perspective view of the design of FIG. 1; FIG. 3 is a front view of the design of FIG. 1; FIG. 4 is a rear view of the design of FIG. 1; FIG. 5 is a first side view of the design of FIG. 1; FIG. 6 is a second side view of the design of FIG. 1; FIG. 7 is a top view of the design of FIG. 1; and, FIG. 8 is a bottom view of the design of FIG. 1. The broken line showing of portions of the firearm are included for the purpose of illustrating environment and forms no part of the claimed design.
